FIG. 2.

INVENTOR

Elmer E. Wickersham,
by G. H. Strong

ATTORNEY

UNITED STATES PATENT OFFICE.

ELMER E. WICKERSHAM, OF SUNNYVALE, CALIFORNIA, ASSIGNOR TO THE YUBA CONSTRUCTION COMPANY, OF SAN FRANCISCO, CALIFORNIA, A CORPORATION OF CALIFORNIA.

CARBURETER.

1,167,457.

Specification of Letters Patent.

Patented Jan. 11, 1916.

Application filed January 26, 1914, Serial No. 814,355. Renewed June 1, 1915. Serial No. 31,619.

To all whom it may concern:

Be it known that I, ELMER E. WICKERSHAM, a citizen of the United States, residing at Sunnyvale, in the county of Santa Clara and State of California, have invented new and useful Improvements in Carbureters, of which the following is a specification.

This invention relates to carbureters.

10 It is the object of the present invention to provide a carbureter with a single air inlet in which sufficient air is introduced at low speed for starting purposes, and which is controlled by a valve for the admission of 15 a larger quantity of air as the speed of the motor increases.

It is a further object of the present invention to provide a carbureter, eliminating as far as possible, auxiliary valves, springs, 20 fuel-valves and complicated adjusting devices commonly employed in carbureters.

It is a further object of the invention to provide a carbureter of such design that the income from the air-inlet is thrown or directed downwardly, and to provide a hot-plate toward which the air current is directed so that fuel vapor drawn from a nozzle is impinged upon or brought into close proximity to the plate so that the heat itself 30 vaporizes all the moisture gathered by the air passing the nozzle, thus raising the temperature of the vapor and imparting to it sufficient latent heat to maintain it in a nearly gaseous form, thus avoiding condensation during the passage from the carbureter to the engine cylinders, thus providing a carbureter so designed that the vaporization of the liquid fuel is aided by the discharge in spray form from the nozzle, and 40 by the vaporizing effect of the hot-plate within the carbureter.

A further and very important object of my present invention is to provide a carbureter involving a structure so designed that 45 a proper proportion of fuel vapor is drawn into the carbureter in proportion to the speed of the motor, this design involving a structure whereby atmospheric pressure is automatically controlled without moving 50 parts, and effecting the volume of discharge from the spray-nozzle of the carbureter constantly in proportion to the speed of the motor, and particularly to provide a carbureter in which the air-pressure in the gaso- 55 lene chamber is automatically varied by the

tension of the vacuum in the carbureter, so that as the suction effect increases at the nozzle, the pressure of air in the gasoline or fuel chamber decreases, and thus the effective head upon the fuel at the nozzle is diminished. 60

Another object of the present invention is to provide a carbureter capable of efficiently vaporizing coal oil, distillate and other lower grade hydro-carbon fuels, means being provided for supplying said fuel to the main chamber of the carbureter, and means also being provided for the supply of the richer hydro-carbon fuel to the carbureter for the purpose of ready and quick starting 70

The invention consists of a carbureter with a gasoline float-chamber, a spray nozzle communicating with said chamber, and means for controlling the degree of pressure 75 in the float-chamber upon the fuel in proportion to the pressure in the vapor-flue of the carbureter.

The invention further consists of the whole, the parts and the combination of 80 parts as hereinafter set forth, and shown in the accompanying drawing in which—

Figure 1 is a central vertical section through the carbureter; Fig. 2 is a horizontal section on the line "X-X" of Fig. 1. 85

The carbureter indicated generally at 2 consists of a fuel-chamber 3 to which may be connected a pipe 4 from a source of supply of liquid fuel, the flow of which is controlled by a suitable valve 5 to which is connected a float 6 which, when elevated by the charge of fuel in the fuel-chamber 3 operates to cut off the flow of fuel. Extending laterally from the float chamber 3 is a shallow channel 7 into which opens a discharge 90 nozzle 8 with a plurality of discharge apertures 9 of fixed size directed downwardly.

The nozzle 8 stands central in an inlet tube 10, in which is movable adjustably a controlling valve 11, the size of which is such as to permit a sufficient quantity of air to enter the flue 10 during the operation of the motor, to which the carbureter may be attached, the air passing through the flues and being directed downwardly along the nozzle 135 8, and impinging upon a hot-plate 12, forming the top of a chamber 13 to which a portion of the hot exhaust gases from the motor may be conveyed through a pipe 14; thence, passing through the chamber 13, and dis- 110

charging at an outlet pipe 15, the hot gases heating the hot-plate 12, and the top wall of the channel 7, and serving at the same time to heat the liquid fuel in the channel 5 7 while passing to the spray-nozzle 8, and heating the vapor passing through the carbureter in the passage-way 16 above the plate 12 which is at right angles to the axis of the air-flue 10. The heated vapor arising 10 from the passage-way 16 passes upwardly through the flue 18, the upper end of which may be connected to the intake, or manifold of the motor.

Within the discharge flue 18 of the vaporizer is mounted a throttle 19 having an operating lever 20 connected by the adjustable link 21 to a lever 22 of the air-valve 11, so that these valves may be adjusted initially to suit given conditions and thereafter remain 15 in such adjustment, and operate simultaneously so that the speed of the engine is controlled by the movement of the throttle 19, and also the volume of air admitted to the carbureter, controlled by the air-valve 11.

It is one of the important features of this invention to design and provide a carbureter in which the over-enrichment of the vapor drawn from the carbureter is effectively and automatically eliminated by so constructing 20 the carbureter that the pressure upon the fuel in the fuel-chamber 3 is constantly controlled by the degree of pressure in the suction-flue 18, so that as the engine increases speed and the pressure falls, or the vacuum 25 increases in the chamber 18, simultaneously there will be a variation of pressure in the fuel-chamber 3, so that the pressure therein will fall as it decreases in the vapor-flue 18, and thus the quantity of fuel drawn 30 from the nozzle 8 through the apertures 9 will be diminished, and conversely, as pressure increases in the vapor-flue 18 a corresponding increase will be effected in the flue-chamber 3, and this increase proportionately 35 increasing the discharge from the nozzle 8. This automatic variation of pressure in the fuel-chamber 3 in proportion to the variation of pressure in the chamber 18 is effected 40 in a very simple manner without requiring 45 in any way the attention of the operator, or the adjustment of any devices whatever after the carbureter has once been set to meet given conditions. The accomplishment of the desired result is produced by providing 50 a means of communication between the suction-chamber 18 and the fuel-chamber 3, this means comprising a duct or aperture 23, which is of such size as will afford the desired tendency of equalization of pressure 55 as between the air-pressure in the fuel-chamber 3 and the pressure of the vapor-chamber 18. The ratio between the pressures in the chambers 3—18 is controlled by providing a port or aperture 24, which opens 60 65 through the wall of the carbureter to estab-

lish communication with the atmosphere to the chamber 3; and in order to control the area of the opening 24 there is provided a suitable valve 25 having a port 26 which may be turned with relation to the port 24, so as to permit the cut-off or increase of flow of air through the port 24 into the chamber 3, such as given conditions of altitude or temperature may require.

The operation and effect of the carbureter 75 is as follows: Assuming that the device has been applied to a motor, and it is desired to start the latter, and that the air-throttle 25 has been adjusted to meet the given conditions; then, as motor is cranked, a suction 80 takes place in the vapor chambers and flues of the carbureter so that air is introduced past the air-valve 11, and this induces a spray of fuel from the nozzle 8 which enriches the air drawn into the engine through the vapor-flue 18. At slow speed, the pressure of air in the chamber 3, which communicates with an atmosphere through the port 24 is substantially the same as atmospheric. Upon the increase of speed of the motor, and 90 with greater suction effect of the air current passing the spray-nozzle 8, the quantity of fuel from the latter is proportionately increased; and ordinarily, without some means being provided, the quantity of fuel 95 introduced would be excessive and thus wastefully enrich the fuel vapor. By my present carbureter, as the suction in the flue 18 increases, it tends through means of the communication afforded by the port 23 to 100 decrease the pressure of air in the fuel-chamber 3 and upon the liquid therein, so that effective head or pressure acting upon the fuel to discharge it through the nozzle 8 is decreased proportionately as the suction 105 in the flue 18 increases.

It is understood that as before stated, the ratio of pressure in the chambers 3—18 is controlled as desired by throttling the air aperture 24 through which communication 110 is established between the atmosphere and the fuel chamber.

This carbureter I have successfully established, and with it effectively vaporized the lower grades of hydro-carbon, such as coal, 115 oil, distillate, etc. When the carbureter is being supplied with these low grade fuels, it is desirable, in order to obtain a quick start, that means be provided for introducing a supply of rich fuel, such as gasolene, 120 and to that end I have attached to channel 7, or at any suitable location to the carbureter a gasolene supply pipe 27 in which is mounted a valve 28, so that when starting the motor the valve 28 may be opened and 125 a quantity of gasolene with sufficient pressure admitted to the channel 7, and this will flow to the nozzle 8 in advance of the oil in the fuel chamber 3. As soon as the motor has started the gasolene may be cut 130

off at the valve 28, and the lower grade of fuel drawn from the chamber 3.

I claim—

1. In a carbureter, a fuel supply chamber, a channel extending laterally from said chamber, a plate located above said channel in spaced relation thereto to form a hot gas chamber, an air inlet tube having its lower end disposed over said plate in spaced relation thereto, a discharge flue to one side of the inlet tube; a nozzle communicating with said channel and extending through the hot gas chamber and said plate and up into the air inlet tube, a valve controlled port communicating with the atmosphere and with said fuel supply chamber, there being a port between said fuel supply chamber and the flue, and means to lead hot gas into and out of the hot gas chamber.
2. In a carbureter, a vertically disposed fuel supply chamber and a horizontal passage leading therefrom, a horizontal hot gas chamber overlying said passage and terminating at its inner end at the inner end of the supply chamber, an air inlet flue having a discharge which overlies the hot gas chamber, a vertical spray nozzle connected to the passage and extending up into the air flue, and an exit passage arranged to have its lower end disposed over said hot gas chamber.
3. In a carbureter, a main fuel supply chamber having a horizontal passage leading therefrom, a carbureting chamber having a floor overlying and spaced vertically from said passage to provide therewith a heating chamber, an air inlet flue leading to said carbureting chamber, and a gas exit pipe, a spray pipe extending from said passage into said flue and having passages ar-

ranged to direct the fuel jets downward toward said floor, said heating chamber extending to said main fuel supply chamber.

4. In a carbureter, a main fuel supply chamber having a horizontal discharge passage, a carbureting chamber, an air inlet flue leading thereto, a plate forming the bottom wall of said carbureting chamber, said plate overlying and spaced vertically from said passage and forming therewith a heating chamber which extends to said main fuel chamber, and a spray pipe connected with said passage and extending through the heating chamber and into said flue, and discharging fuel downward toward said plate, whereby the sprayed fuel is brought into direct contact with the heated bottom wall of the carbureting chamber.

5. In a carbureter, a main fuel supply chamber, a horizontal discharge passage leading therefrom, a carbureting chamber located over said passage and having a plate constituting its floor which is spaced vertically from said passage and forms therewith a heating chamber that extends to said main fuel chamber, air inlet and gas discharge flues in communication with the carbureting chamber, and a fuel spray pipe connected with said passage and extending through the heating chamber and into the air inlet flue and arranged to discharge the fuel downward against said plate.

In testimony whereof I have hereunto set my hand in the presence of two subscribing witnesses.

ELMER E. WICKERSHAM.
